UNITED STATES PATENT OFFICE.

JOHN W. FOSTER, OF WESTFIELD, MASSACHUSETTS, ASSIGNOR TO THE FOSTER MACHINE COMPANY, OF SAME PLACE.

TWISTING ATTACHMENT FOR WINDING-MACHINES.

SPECIFICATION forming part of Letters Patent No. 499,666, dated June 13, 1893.

Application filed August 6, 1892. Serial No. 442,333. (No model.)

To all whom it may concern:

Be it known that I, JOHN W. FOSTER, of Westfield, county of Hampden, State of Massachusetts, have invented an Improvement in 5 Twisting Attachments for Winding-Machines, of which the following description, in connection with the accompanying drawings, is a specification, like letters and figures on the drawings representing like parts.

10 This invention has for its object the production of devices adapted for ready attachment to a spooling machine whereby two or more yarns taken from cops, bobbins, or spools, may be twisted together and wound 15 upon a suitable yarn receiver.

I have chosen to illustrate my present invention as applied to a spooling machine of a form heretofore patented to me, No. 404,831, June 11, 1889, and in the drawings the driving 20 drum or shell roll is represented for convenience as having its axis parallel to the side of the frame, but this is immaterial, and instead, the said drum or roll may stand at right angles thereto as in United States Patents 25 Nos. 459,039 and 459,040.

Prior to my invention it has been customary to take cops of yarn and without twisting, wind the yarn, one or more strands upon a spool, and these spools having the yarns so applied have been put into a twister and two or 30 more of said yarns have been twisted together by or through a spindle, but in my invention, the yarn on the cops or bobbins on which they were spun are doubled and twisted 35 and wound in one operation on yarn carriers, such as spools or cones.

Figure 1, in vertical section and elevation represents a sufficient portion of a spooling machine with my present improvements added 40 to enable my invention to be understood; Fig. 2, an enlarged vertical section of my improved doubling and twisting device detached from the machine. Fig. 3, is a view looking down on Fig. 2, below the dotted line x. Fig. 4, is 45 a view looking up from the dotted line x'; and Fig. 5, is a detail to be referred to.

The frame-work A, the cylinder e⁴ on the shaft e⁵, the shaft e' having suitable wheels e and located within the shell roll h constituting 50 a driving drum to rotate the yarn receiver a³, are and may be all substantially as in the patent referred to, said yarn receiver being

either cylindrical or conical, or of any known and suitable construction, but instead of the shell roll, I might employ a solid drum. I 55 have herein shown but one driving drum, but it will be understood that a machine embodying my invention will contain a series of said drums along one or both sides, and when the said drums are used parallel to the side of 60 the frame, the wheels e for rotating them, may all be arranged on one and the same shaft e' arranged lengthwise of the machine, and driven in any usual or suitable manner. My patent of the United States, No. 404,831, 65 shows one plan of driving shafts suitable for rotating said drums when their axes are at right angles to the side of the frame. The traverse guide h³ will preferably be of the form represented in United States Patent No. 70 459,039, it having a foot to enter a crossing groove in the shell roll h constituting the drum, said guide sliding on rods 2, 2, supported by suitable arms or brackets as 75 3 suitably attached to the frame-work A. The lower girth A' of the frame has connected to, or is provided with a bracket a, which latter supports a stand a' on which is a stud a² which 80 serves as a support for a pulley a³ preferably having a surface by which to frictionally engage and rotate the head a⁴ carrying the spindles a⁵, two or more of said spindles containing and presenting the yarns to be twisted and wound into spool form, the drawings representing the said yarns as in the form of cops as 85 when taken from a mule. The head at its lower side is shown as provided with a friction face a⁶ which may be of cloth, leather, india-rubber, or other usual material. The hub of the pulley a³ is represented as provided with a 90 belt pulley a⁷ which receives the belt a⁸ deriving its motion from the cylinder e⁴. The bracket and stand are represented as confined together by a hollow stud b having a shoulder to rest on the bracket, a nut b' being 95 shown as screwed upon the lower threaded end of the stud. This stud receives through it a stop-motion rod c, and near its lower end the stud has a transverse opening for the reception of a pawl c', the pawl being represented as connected adjustably with the rod c by a suitable screw c². The outer end of the pawl c' engages a lifter c³ mounted loosely on a stud c⁴, said lifter being so constructed 100

that when turned on or about the stud, the lifter, the shape of which is shown by dotted lines Fig. 1, will act by one of its corners or by its surface to lift the head a^4 from the wheel a^3 and thus stop the rotation of the head with its spindles, or yarn holders. This lifting device is represented as a disk or button having a portion of its periphery slabbed off as in Figs. 1 and 5, leaving two corners 10 4, 4, see Fig. 5. The head a^4 has, as shown, a hollow hub 5 which receives a tube d , which at its upper end supports a disk d' having its periphery incased by a clearer d^2 , preferably a piece of cloth, the purpose of which is by 15 its action against the yarn to give tension thereto between the rigid guide eye d^3 below the disk, one eye for each yarn, and the eye 6 above the disk, the latter eye being carried by a drop lever f pivoted at f' on a suitable stud f^2 in the disk. The stop-motion rod has fast on it a collar g , see Fig. 2, the collar serving to limit the descent of the rod, and above the collar, the rod has applied to it 20 frictionally a clutch g' provided with depending pins or projections 8. This clutch rests at its lower side on the collar, and the pins lie outside the collar and in the line of movement of the inner ends of the drop levers f , but when a yarn going to the guide eye f^4 25 breaks so as to let a drop wire fall, then in such case the inner end of the drop wire as the disk rotates meets a pin next to it of the clutch and acting against the said pin rotates the said clutch, and with it the stop-motion rod c far enough to turn the lifting device 30 c^3 and break the driving contact between the head a^4 and wheel a^3 . Above the clutch the rod c is provided with a friction device g^4 shown as a piece of leather or other suitable 35 material held against the clutch by suitable devices as nuts. The yarn to be doubled and twisted is led from the eyes 6 to the stationary eyes f^4 and thence preferably over a glass rod m to the traverse device h^3 before described.

From the foregoing it will be understood that the doubling and twisting devices, shown detached in Figs. 2, 3 and 4, may be readily attached to a spooling machine so that the yarns carried by the attachment, may be doubled and twisted on their way to the spools. It will be understood that should the driving drum be at right angles to the side frame as in Patent No. 459,039, that in such event the 55 yarn will have to be presented to the eye of the traverse guide, as in United States Patent No. 404,831.

In practice the machine herein described will or may have a suitable stop-motion to 60 stop the rotation of the winding drum h at substantially the same instant that the head a^4 is stopped, but I have not herein shown such mechanism, as it has been made the subject matter of another application, Serial 65 No. 442,332, filed August 7, 1892. The clutch is permitted to slip to thereby avoid breaking the pins of the clutches.

This invention is not limited to the exact construction shown for the traverse guide, or the roll for supporting the yarn on its way to the said guide, nor to the exact construction shown for the lifting device and its actuating mechanism,—so long as the head carrying the spindles is stopped in its rotation by or through mechanism extending through the hollow spindle carrying the head,—nor to the exact form of stop-motion devices for the 70 yarns being doubled and twisted, nor is this invention necessarily limited to the form shown of the driving drum, although the shell roll form of drum is the best form known to me.

By the term "cop" as used in the claim I intend to include a wound mass of yarn on a bobbin or tube.

Having described my invention, what I claim as new, and desire to secure by Letters Patent, is—

1. A hollow spindle; a rotating head connected thereto; a series of spindles fixed on 90 said head and adapted to receive and hold masses of yarn taken directly from the spindle of a spinning machine; a device to rotate said head; a series of drop levers; a hollow stud to support said spindle, a drop rod 95 extended through said spindle and stud, and devices actuated by said rod to arrest the rotation of said head, combined with a spooling mechanism consisting essentially of a drum to rotate the spool or device upon which the 100 twisted yarn is to be wound, and a traverse mechanism whereby the spun yarns may be directly doubled, twisted and wound all at a single operation, substantially as described.

2. The rotary driving drum of a spooling 105 machine, and its co-operating traverse guide, combined with a rotating head adapted to receive and carry masses of yarn taken directly from a spinning machine; a hollow spindle upon which said head is mounted; a 110 stop motion rod extended through said spindle; a lifter adapted to be actuated from said rod; and drop levers to control the movement of said rod, the combination being and operating substantially as described, whereby 115 upon the breaking of a yarn the lifting device stops the rotation of the head, substantially as described.

3. The rotating head, the hollow stud about 120 which it rotates, a connected disk having drop wires, and means to rotate said head, combined with a lifting device to lift the rotating head from its actuating means, a stop rod, a clutch thereon, and means between the said stop-rod and lifting device, to operate, 125 substantially as described.

In testimony whereof I have signed my name to this specification in the presence of two subscribing witnesses.

JOHN W. FOSTER.
